UNITED STATES PATENT OFFICE.

LEWIS C. VAN RIPER, OF CHICAGO, ILLINOIS, ASSIGNOR TO BRIGHT MANUFACTURING COMPANY, OF CHICAGO, ILLINOIS, A CORPORATION OF SOUTH DAKOTA.

ENVELOP.

958,785.

Specification of Letters Patent. Patented May 24, 1910.

Application filed March 14, 1910. Serial No. 549,142.

To all whom it may concern:

Be it known that I, LEWIS C. VAN RIPER, a citizen of the United States, residing at Chicago, county of Cook, and State of Illinois, have invented certain new and useful Improvements in Envelops, of which I do declare the following to be a full, clear, and exact description, reference being had to the accompanying drawing, forming part of this specification.

The invention has relation, particularly, to that class of envelopes intended for the transmission through the mails of printed matter, such as catalogues, circulars or the like, the construction of the envelop being such as to securely retain the inclosed matter while permitting it to be readily opened for the purpose of inspection; and the invention is designed, more especially, as an improvement upon the construction of envelop set forth in Letters Patent No. 941,392, granted to me November 30, 1909.

Figure 1 is a plan view of my envelop in unfolded position. Fig. 2 is a view similar to Fig. 1, but with the supplemental portions of the side flaps folded. Fig. 3 is a view showing the envelop partially completed. Fig. 4 is a view showing the envelop complete. Fig. 5 is a view in cross section on line 5—5 of Fig. 4.

The general construction of the envelop blank embraced by my present invention is the same as that set forth in my hereinbefore mentioned Letters Patent No. 941,392. That is to say, the envelop comprises a front portion 1, side flaps 2 and 3 which, when folded and sealed, constitute the back portion of the envelop, an end flap 4 that corresponds with the usual sealing flap of the envelop and an unsealed inspection flap 5.

The precise dimension and shape of the body and flaps of the envelop may be varied as desired.

Across the interior of the body of the envelop extends the supplemental strip 6 which, as in my aforesaid Patent No. 941,392, will coöperate with the flaps 2 and 3 in forming a pocket to receive the unsealed end flap 5 of the envelop. In the envelop set forth in my Patent No. 941,392, the supplemental strip extended merely between the lines 7 and 8 whereon the flaps 2 and 3 were folded, but in my present invention the end portions 6^a and 6^b of the supplemental strip 6 extend across the lines 7 and 8 and overlap

the flaps 2 and 3, as shown. The flaps 2 and 3 are provided respectively at their ends with supplemental flaps 2^a and 3^a, the purpose of which will presently appear.

In forming my improved envelop, the blank will be cut with the several flaps 2, 2^a, 3, 3^a, 4 and 5 and gum will be applied along the edges of the flaps 2, 2^a, 3, 3^a and 4 and gum will also be applied transversely from side to side of the flaps 2 and 3, as shown at 60 2^c and 3^c. The supplemental strip 6 will be placed in position with its ends overlapping the flaps 2 and 3 and the upper corners of the strip 6 will be united by the gummed portions 2^c and 3^c to said flaps, as clearly 65 shown in Fig. 1 of the drawing. By this means the supplemental strip 6 will be securely held in position while the folding of the envelop is being effected, and inasmuch as the supplemental strip 6 is thus held at 70 both ends, all danger of the displacement of the strip after it has been set in position, will be avoided. The supplemental flaps 2^a and 3^a will be turned over on to the flaps 2 and 3, and the inner ends of these supplemental flaps 2^a and 3^a will be united to the 75 ends 6^a and 6^b of the supplemental strip 6, as clearly shown in Fig. 2 of the drawing.

By forming the supplemental strip 6 with the end extensions 6^a and 6^b overlapping the 80 side flaps 2 and 3, two distinct advantages are attained, viz., first, the supplemental strip 6 is securely gummed at both ends to the flaps 2 and 3, so that during the subsequent forming operations the strip will be 85 prevented from shifting out of place and, second, the end portions 6^a and 6^b of the supplemental strip 6 will effectively strengthen both ends of the envelop at the points which are subjected to the greatest strain in the 90 operation of opening and closing the envelop when its contents are to be inspected. After the strip 6 has been set in position and the supplemental flaps 2^a and 3^a have been 95 folded down, as shown in Fig. 2 of the drawing, the unsealed flap 5 will then be turned over on to the supplemental strip 6, as shown in Fig. 3, and the flap 2 will be folded over the body portion 1 and over the supplemental strip 6 and flap 5, and the layer of 100 gum 2^c will firmly unite the flap 2 to the supplemental strip 6, adjacent the innermost edge of said strip. The flap 3 will then be turned over upon the body 1, the supplemental strip 6, and the flap 5, and the outer 105

gummed edge of the flap 3 will overlap and be sealed to the edge of the flap 2, while the gummed surface 3^c of the flap 3 will be securely united to the supplemental strip 6

5 adjacent its innermost edge.

It will thus be seen that the unsealed flap 5 will be held within a pocket formed by the supplemental strip 6 and the flaps 2 and 3, but after the printed matter or the like has 10 been placed within the completed envelop and the usual flap 4 has been sealed, the unsealed flap 5 can be readily withdrawn and replaced when the contents of the envelop are to be inspected. Inasmuch as both 15 ends of the pocket that receives the unsealed flap 5 are reinforced by the extensions 6^a and 6^b of the supplemental strip 6, the danger of tearing out the ends of the pockets is reduced to a minimum. So, also, thelapping 20 of the supplemental flaps 2^a and 3^a on to the ends 6^a and 6^b of the strip 6 serves to materially strengthen such end portions of the strip.

Inasmuch as the gummed surfaces 2^c and 25 3^c of the flaps 2 and 3 extend from side to side thereof and are in line with the upper portion of the supplemental strip 6, all the gumming of the blank may be done at one operation and it is not necessary otherwise 30 to apply gum to the surface of the supplemental strip, since the inner portions of the gummed surfaces 2^c and 3^c serve to unite the upper corners of the strip 6 to the flaps 2 and 3.

35 Having thus described my invention, what I claim as new and desire to secure by Letters Patent, is:—

1. An envelop comprising a front portion, a back portion, flaps, and an interior supplemental strip for forming with the back 40 portion a pocket to receive one of the flaps,

45 said supplemental strip being gummed to the back portion and having both of its ends extending over and gummed to the flaps adjacent thereto.

2. An envelop comprising a front portion, a back portion formed of side flaps, a sealing flap, an inspection flap and an interior supplemental strip for forming with the back portion a pocket to receive said inspection flap, said supplemental strip being longer than the interior dimension of the envelop and overlapping each of said side flaps, each of said side flaps being provided with a gummed surface extending from side 55 to side thereof in line with the upper portion of said supplemental strip, said gummed surface serving to unite the upper corners of said strip to the side flaps while said flaps are in unfolded position and serving, when 60 the side flaps are folded, to unite them to the supplemental strip adjacent its upper edge.

3. An envelop comprising a front portion, a back portion formed of flaps carried by 65 the front portion and a separate supplemental strip, two of said flaps and said supplemental strip being secured together to form a pocket in said back portion between said flaps and said supplemental strip and 70 open along one edge of the envelop to removably receive an inspection flap, said supplemental strip having extended end portions overlapping the flaps that form the back portion and secured thereto, and said two 75 flaps having supplemental flaps folded over the end portions of said supplemental strip.

LEWIS C. VAN RIPER.
